CLAIM

The ornamental design for a tissue marker for intracorporeal site identification, as shown and described.

DESCRIPTION

FIG. 1 is a perspective view of a tissue marker for intracorporeal site identification showing the new design, as viewed from the front lower right;

FIG. 2 is a perspective view of the tissue marker, as viewed from the rear upper right;

FIG. 3 is a perspective view of the tissue marker, as viewed from the rear lower right;

FIG. 4 is a perspective view of the tissue marker of FIG. 3, rotated clockwise 90 degrees;

FIG. 5 is a front view of the tissue marker;

FIG. 6 is a right side view of the tissue marker;

FIG. 7 is a left side view of the tissue marker;

FIG. 8 is a top view of the tissue marker; and,

FIG. 9 is a bottom view of the tissue marker.

Terms used above with respect to orientation, e.g., front, rear, upper, lower, right, left, top, bottom, etc., are terms of convenience used to distinguish between the various views, and are not necessarily reflective of the orientation of the tissue marker before or after being placed at the intracorporeal site. Preferably, the largest dimension of the tissue marker is less than 5 millimeters.

1 Claim, 2 Drawing Sheets
